COMBINED ADVERTISING SIGN AND CLOCK

Solomon H. Shapiro, New York, N. Y.

Application May 10, 1955, Serial No. 35,902

Term of patent 7 years

(Cl. D1—12)

Fig. 2.

Fig. 3.

Fig. 1.

Fig. 1 is a front view of a combined advertising sign and clock showing my new design, Fig. 2 is a top plan view thereof and Fig. 3 is a side view of Fig. 1 as seen from the left. The rear of Fig. 1 is similar to the side shown.

I claim:

The ornamental design for a combined advertising sign and clock, substantially as shown and described.
